CLAIM

The ornamental design for a table as shown and described.

DESCRIPTION

FIG. 1 is a top-front-right perspective view of a table according to the claimed design.

FIG. 2 is a top view of the table of FIG. 1.

FIG. 3 is a bottom view of the table of FIG. 1.

FIG. 4 is a right side view of the table of FIG. 1.

FIG. 5 is a left side view of the table of FIG. 1.

FIG. 6 is a front view of the table of FIG. 1; and,

FIG. 7 is a rear view of the table of FIG. 1.

The dash-dash broken lines in the drawings illustrate portions of the table that form no part of the claimed design. The shade lines in the drawings illustrate contours of the table and form no part of the claimed design.

1 Claim, 5 Drawing Sheets
